UNITED STATES PATENT OFFICE

JOHN CHARLES KELLER, OF CHICAGO, ILLINOIS, ASSIGNOR TO KELLER PNEUMATIC FOOTWEAR COMPANY, OF CHICAGO, ILLINOIS

PNEUMATIC FOOTWEAR CONSTRUCTION

Application filed February 2, 1931. Serial No. 513,020.

My invention relates to improvements in footwear constructions of the pneumatic type, and it consists in the combinations, constructions, and arrangements herein described and claimed.

An object of my invention is to provide a pneumatic heel construction wherein a greater cushioning effect is produced than in other heels of the type, due to the novel construction.

A further object of my invention is to provide a pneumatic heel in which the cushioning means is readily brought to play, but which is amply provided with sufficient resisting material to prevent undue wear of the heel.

A further object is to provide a pneumatic heel construction which is simple and which, therefore, may be made at a relatively low cost, but which has, nevertheless, a maximum cushioning effect.

Other objects and advantages will appear in the following specification, and the novel features of the invention will be particularly pointed out in the appended claims.

My invention is illustrated in the accompanying drawing, forming part of this application, in which

Figure 1 is a sectional view through a portion of a shoe and heel,

Figure 2 is an enlarged front end view of the heel before it is applied to the shoe or boot,

Figure 3 is a bottom plan view of the heel shown in Figure 2,

Figure 4 is a bottom plan view of a heel for a lady's shoe, and

Figure 5 is an end view of the heel shown in Figure 4.

Referring to the drawing, I have shown therein a heel comprising a body portion 1, comprising in reality side walls, these side walls being provided with integral internal lug portions 2 having nail holes 3. That portion 4 between the side walls is hollow to provide an air space.

An integral bottom portion 5 is provided which, as shown in Figures 1 and 2, is bowed or curved outwardly. This portion, it will be observed, is relatively thin as compared with

the walls 1 in order that when the weight of the wearer is placed on the body portion, it may easily flex. Covering the recess 4 is a top portion 6 which has a normally outwardly curved or bowed portion, see Figure 2. The top surface of the portion 6 is normally dished to provide a flange portion 7 at the outer edges thereof. The portion 6 is vulcanized to the walls 1 so as to form one piece having the air space 4 therein.

From the foregoing description of the various parts of the device, the operation thereof may be readily understood. The heel thus formed may be applied to the shoe in the ordinary manner by driving nails 8 through the nail holes 3, washers 9 being provided in the side walls against which the heads of the nails bear. When the heel is in position, the flange 7 is brought flush with the flat bottom portion of the layer 10 of the shoe or boot, and the bowed portion 6 is also brought flat as shown in Figure 1. The purpose of dishing the member 6 is to place the outer edges under tension so that they will cling tightly to the member 10 to which the heel is attached.

When the heel is walked on, the bowed portion 5 is placed under pressure, and being relatively thin, it will tend to give, thus compressing the air in the air space 4 and exerting immediately a cushioning effect. When the full weight of the wearer comes on the heel, it will be flattened out flush with the bottom portion of the side walls 1. The latter, being relatively thick, will bear a portion of the weight and prevent any undue flexure. When the heel is lifted, the compressed air tends to bring the portion 5 into its expanded condition so that it will be again brought into play when the next step is taken.

In Figures 2 and 3 I have illustrated a heel for a man's shoe. In Figures 4 and 5 I have shown a modification for a lady's shoe. In both of these forms, however, the principle is the same. It is essential to the purpose of my invention that there be a bowed portion such as that shown at 5 in Figure 1, and at 5X in Figures 4 and 5, which may be flexed to exert the cushioning effect before the main weight comes on the side walls of the heel,

but in which the side walls form an additional supporting member and also form a body portion for confining the air.

I claim:

- 5 1. As an article of manufacture, a pneumatic cushion heel for shoes including a resilient body portion having a hermetically sealed cavity formed by outwardly extending integral and continuous concavo-convex top and bottom walls and upstanding side walls of said body.
- 10 2. As an article of manufacture, a pneumatic cushion heel for shoes including a resilient body portion having a hermetically sealed cavity formed by outwardly extending integral and continuous concavo-convex top and bottom walls and upstanding side walls of said body, all of said walls being provided on their inner sides with spaced-apart integral upright posts.
- 15 3. As an article of manufacture, a pneumatic cushion heel for shoes including a resilient body portion having a hermetically sealed cavity formed by outwardly extending integral and continuous concavo-convex top and bottom walls and upstanding side walls of said body, all of said walls being provided on their inner sides with spaced-apart integral upright posts, said side walls and said 20 posts having common nail openings perforating the outer central portion of said cylindrical posts.

Signed at Chicago in the county of Cook and State of Illinois this 9 day of Jan., A. D. 35 1931.

JOHN CHARLES KELLER.
